UNITED STATES PATENT OFFICE.

CHARLES E. GODLEY, OF DETROIT, MICHIGAN, ASSIGNOR, BY MESNE ASSIGNMENTS,
TO EDMUNDS & JONES CORPORATION, OF NEW YORK, N. Y., A CORPORATION OF
NEW YORK.

LAMP-DOOR-SECURING MEANS.

1,202,057.

Specification of Letters Patent. Patented Oct. 24, 1916.

Application filed February 4, 1916. Serial No. 76,087.

To all whom it may concern:

Be it known that I, CHARLES E. GODLEY, a citizen of the United States, and residing at Detroit, in the county of Wayne and 5 State of Michigan, have invented a new and Improved Lamp-Door-Securing Means, of which the following is a specification.

This invention relates to means for securing the lens-rings or other door-frames of 10 vehicle and other lamps to the bodies or casings thereof, and its object is to provide resilient lamp-door securing means which will hold the door closed and effectively prevent the door from rattling.

15 This invention consists in the combination of a lamp body having a door casing comprising a novel inwardly and forwardly extending flange, a door frame adapted to fit against the door casing, and novel resilient 20 means mounted on the door frame and adapted to engage the inner side of said flange to hold the door against the casing.

In the accompanying drawing, Figure 1 is 25 an elevation of a lamp provided with a door that is shown in section, the improved door-securing means being shown in proper position. Fig. 2 is an elevation of the door-securing means of the structure shown in 30 Fig. 1. Fig. 3 is an elevation of a modified form of door-securing means. Fig. 4 is a central vertical section of the door and the door casing of a slightly modified form of lamp. Fig. 5 is a section on the line 5—5 of Fig. 4.

35 Similar reference characters refer to like parts throughout the several views.

The lamp shown in the drawing comprises a body 1, head 2 and font 3. Secured to the body is a leaf 4 of a door hinge, the leaf 5 being secured to the lens-ring 6 of the door, and to the leaf 4 by means of a pintle 7. A lens 8 is held in position in the lens-ring by means of a spring ring 9 of well known construction. The lens-ring will be hereafter termed the frame of the door. Its inner edge is in the form of a grooved flange 10 that receives the lens 8 and the ring 9, while its outer edge is in the form of a stiffening bead 11.

50 The front of the body is in the form of a circular door casing and consists of a flaring portion 13 to which the leaf 4 of the hinge is secured, a ledge 14 against which the bead 11 may rest, and an inwardly and forwardly extending flange 15. The bead 11

of the door frame fits around this flange and against this ledge and the door is therefore properly positioned by this door casing. A thumb piece 16 may be secured to the door frame so that the door may be swung away 60 from the casing.

To secure the door to the casing, a ring 17 of spring wire is secured to the door frame just within the bead 11, preferably by bits of solder 18, or by spot welding. A portion 19 of this ring opposite the thumb piece is bent away from the bead 11 in order that it may be free to move, and is then bent inwardly, rearwardly and then both inwardly and rearwardly so that the hook 20 is formed 70 intermediate the ends of this free portion 19.

When the door is swung up to the position shown in Fig. 1, the inclined end of the hook engages under the flange 15 and is depressed thereby, the hook and the part 19 of the 75 spring ring yielding to permit the hook to pass under this flange until the shoulders 21 thereof are back of the ledge 14, in which position the hook will firmly hold the door against the casing. Considerable force is 80 required to swing the door away from the body.

When no hinge between the body and door is employed, the spring 24 may be formed with a number of hooks 25, three preferred, 85 of the same type as the hook 20 just described. The thumb-piece 16 is secured to the door, if desired, adjacent one of the hooks to assist in detaching the door. This spring 24 may also be attached to the door by means of spots 26 of solder or by spot welding. While the spring 17 is shown to be a complete ring, the portions beyond the spots 18 of solder adjacent the parts 19 may be omitted, although the entire ring is preferred as it is much stiffer than a shorter piece of the same metal.

It will be apparent that the details of the door casing and frame can be reversed, that is, that the spring may be mounted on a 100 properly designed casing and that the retaining members of this spring may engage a flange on the door frame. In Figs. 4 and 5, the flaring portion 13 of the lamp body terminates in a bead 30, similar to the bead 11 on the door frame, and this bead 30 may be considered to be a door casing. The lens-ring 6 may be hinged to this casing and its lens 8 may be secured in position by the 105 spring ring 9.

The rear or outer edge of the door frame extends inwardly and rearwardly in the form of a flange 31. A spring 32 in the form of a wire ring may be secured at intervals within the flaring portion 13 of the body by bits 33 of solder, and this spring may have free portions 34 that join in forming the hooks 35 which are similar in their action to the spring hooks 20 previously described, and as stated before, these hooks may be as numerous as desired.

The details and proportions of this construction may be modified by those skilled in the lamp art without departing from the spirit of my invention.

I claim:—

1. Lamp door securing means consisting of a ring of spring wire secured to the door at separated points, a hook being formed on the wire intermediate these points and adapted to be forced radially inward under a flange on the body of the lamp.

2. In a lamp, the combination of a body having a circular ledge and an inwardly and forwardly extending flange, a door frame hinged to said body and having an external edge fitting against the ledge and around said flange, and a resilient spring secured to said frame at spaced points and formed into a rearwardly projecting hook between said points which hook is adapted to be forced in below said flange, said hook having a substantially radial shoulder adapted to engage back of said ledge.

3. In a lamp, the combination of a body having a circular ledge and an inwardly and forwardly extending flange, a door having an external edge fitting against the ledge and around the flange, and a resilient spring ring secured at intervals to said door and formed into rearwardly projecting hooks which are adapted to be forced in against the inner face of said flange, said hooks having substantially radial shoulders adapted to engage back of said ledge.

4. In a lamp, the combination of a body having a circular opening, an inwardly extending ledge and a forwardly and inwardly extending flange at the inner edge of the ledge, a door frame having its outer edge in the form of a bead adapted to fit around

said flange in engagement with the ledge, and a resilient hook mounted on the door and adapted to engage the flange and ledge and thereby secure the door to said body. 55

5. In a lamp, the combination of a body having a circular opening, an inwardly extending ledge and a forwardly and inwardly extending flange at the inner edge of the ledge, a door frame having its outer edge in the form of a bead adapted to fit around said flange in engagement with the ledge, and a resilient wire ring secured to the inner side of said door frame at intervals and formed with a hook to engage the ledge to hold the door in position.

6. In a lamp, the combination of a body having a circular opening, an inwardly extending ledge and a forwardly and inwardly extending flange at the inner edge of the ledge, a door frame having its outer edge in the form of a bead adapted to fit around said flange in engagement with the ledge, and a resilient wire ring secured to the inner side of said door frame at intervals and formed with a series of hooks to engage the ledge to hold the door in position.

7. In a lamp, the combination of a body having a circular opening and a door casing surrounding said opening, a door to fit the casing, one of said members having a flange extending into the other member which fits around said flange, and a resilient wire ring secured to the inner side of the external member at intervals and formed with a hook movable axially of the opening in the body to engage back of said flange and to hold the door in position.

8. In a lamp, the combination of a body having a circular opening and a member surrounding said opening, a door comprising a lens and a member supporting the lens, one of said members being formed with a flange extending into the other, and a ring of spring wire secured to the exterior member and having a hook formed thereon adapted to be forced axially of the opening in the body under said flange to hold the door in position on the body. 95

In testimony whereof I sign this specification.

CHARLES E. GODLEY.
